(57) **CLAIM**

The ornamental design for a rudder pedal plate bracket with apertures for a gaming chair assembly, as shown and described.

DESCRIPTION

FIG. 1 is a perspective view of a rudder pedal plate bracket with apertures for a gaming chair assembly in accordance with the present invention;

FIG. 2 is an elevational left-side view (of which the elevational right-side view is the same) of the rudder pedal plate bracket with apertures for a gaming chair assembly in FIG. 1;

FIG. 3 is an elevational front view (of which the elevational rear view is the same) of the rudder pedal plate bracket with apertures for a gaming chair assembly in FIG. 1;

FIG. 4 is a top plan view of the rudder pedal plate bracket with apertures for a gaming chair assembly in FIG. 1; and,

FIG. 5 is a bottom plan view of the rudder pedal plate bracket with apertures for a gaming chair assembly in FIG. 1.
